Primary Examiner — Patricia A Palasik

(57) **CLAIM**

The ornamental design for a solar powered bicycle repair station, as shown and described.

DESCRIPTION

FIG. 1 is a front elevational view of a solar powered bicycle repair station, showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front and left side perspective view thereof; and,

FIG. 8 is a rear and right side perspective view thereof.

1 Claim, 5 Drawing Sheets
